BY Richard D. Daven,

ATTORNEY

UNITED STATES PATENT OFFICE.

FLOYD HAROLD HORTON, OF ATLANTA, INDIANA.

BROOM-HOLDER.

1,297,351.

Specification of Letters Patent. Patented Mar. 18, 1919.

Application filed January 16, 1918. Serial No. 212,070.

To all whom it may concern:

Be it known that I, FLOYD HAROLD HORTON, a citizen of the United States, residing at Atlanta, in the county of Hamilton and

5 State of Indiana, have invented certain new and useful Improvements in Broom-Holders, of which the following is a specification.

My invention relates to broom holders and the principal object thereof is to provide a 10 broom holder which will effectively retain the broom in a position where the same may be readily grasped and removed therefrom.

A second object of the invention is to provide a broom holder which will support the 15 broom effectively and yet will not mar the handle of the same.

Another object of the invention is to provide a broom holder which will positively support the broom against movement and 20 which is held in such position by its own weight.

Another important object of my invention resides in the provision of a broom holder which consists of few parts, which may be 25 readily assembled and disassembled, and which may be manufactured and placed on the market at a minimum cost.

The above objects together with others will be fully brought out in the following 30 specification and the inventive features explicitly defined in the appended claims.

The invention consists of combinations, constructions, arrangements and operations which will be hereinafter specifically set 35 forth and illustrated in the accompanying drawings, wherein:—

Figure 1 is a front elevation of a broom holder constructed in accordance with my idea and supporting a broom therein, the 40 broom being shown in dotted lines,

Fig. 2 is a side elevation of the same,

Fig. 3 is a view similar to Fig. 2 with the broom removed, the full line position of the device being the position for holding the 45 broom, while the dotted line position illustrates the manner in which the movable part of the device is moved in order to release the broom, and

Fig. 4 is a transverse sectional view taken 50 on the line 4—4 of Fig. 1.

Like characters of reference designate like parts in all the views.

Referring in detail to the drawings, the 55 numeral 5 designates an elongated block which is secured to the wall or any other support through the medium of fastenings 6.

Secured to the front face of the block 5 adjacent its lower end is a block or clamping jaw 7 which is secured to the block 5 through the medium of a fastening 8. The outer 60 longitudinal or the vertical face of the block 7 is formed with a substantially semi-cylindrical groove 9 which is adapted to conform to the curvature of the broom handle.

A movable jaw or block 10 is provided 65 which is also provided with a semi-circular longitudinal groove 11 which is adapted to accommodate the broom handle at a point diametrically opposite that point engaged by the jaw 7. The groove 11 in the block 10 70 and the groove 9 in the block 7 each are lined with sandpaper or other rough material, in order to prevent the broom handle from slipping through the jaws.

A hinge connection or bracket consisting 75 of a pair of wires 12 and 13 each has one extremity loosely engaged with one of the side longitudinal faces of the block 10. These wires 12 and 13 are twisted together as at 14 at their medial portions and extend in 80 opposite directions, and thence bent at right angles and then inwardly to afford trunnions 15 which are mounted in bearings 16 on the block 5.

From the disclosure it will be obvious that 85 when the broom handle is placed between the jaws 7 and 10 in the manner shown in Fig. 2, the broom will be held in place by its own weight, and that upon the moving of the block 10 or broom handle upwardly 90 so that the block 10 occupies the position shown in dotted lines in Fig. 3, the broom may be readily released.

This disclosure is merely illustrative and I wish to here state that the invention can 95 be embodied in constructions other than the one herein specified, and that my limits of such embodiment are only governed by the subjoined claims.

What is claimed, is:—

1. A broom holder comprising a supporting plate, a jaw fixedly secured to said plate, arms hingedly connected to the plate above said jaw, and a second jaw releasably carried by said arms and arranged to coöperate 105 with said first mentioned jaw.

2. A broom holder comprising a supporting plate, a jaw fixedly secured to said plate, parallel clamping arms secured together at one end to form a loop and hingedly connected with said supporting plate above said 110 jaw and a second jaw releasably clamped

between the free ends of said arms and co-operating with said first mentioned jaw.

3. A broom holder comprising a supporting plate, a jaw fixed to said plate, a pair of parallel clamping arms secured together at one end and hingedly connected to the plate at a point above said jaw, the free ends of said arms being extended inwardly at right angles, and a second jaw provided with side

sockets loosely receiving the inturned ends 10 of said arms and arranged to coöperate with said first mentioned jaw.

In testimony whereof I affix my signature in presence of two witnesses.

FLOYD HAROLD HORTON.

Witnesses:

KENNETH EHMANN,
MILDRED SHAFFER.
